UNITED STATES PATENT OFFICE.

HENRY PRICE BALL, OF NEW YORK, N. Y., ASSIGNOR TO S. STERNAU & CO., OF BROOKLYN, NEW YORK, A COPARTNERSHIP COMPOSED OF SIGMUND STERNAU AND LIONEL STRASSBURGER.

DESIGN FOR A LEG FOR PORTABLE STOVES.

49,251.

Specification for Design.

Patented June 27, 1916.

Application filed November 8, 1915. Serial No. 60,181. Term of patent 7 years.

To all whom it may concern:

Be it known that I, HENRY PRICE BALL, a citizen of the United States, resident of borough of Brooklyn, county of Kings, city and State of New York, have invented a new, original, and ornamental Design for a Leg for Portable Stoves, of which the following is a specification, reference being had to the accompanying drawings, forming a part thereof.

In the drawings, Figure 1 is a top view,

Fig. 2 is a side view; and Fig. 3 is an end view of a portable-stove leg embodying my invention.

I claim:

The ornamental design for a leg for a portable stove, substantially as shown.

HENRY PRICE BALL.
